ARC-LAMP.

Specification of Letters Patent.

Patented Dec. 5, 1911.

Application filed March 7, 1907. Serial No. 361,050.

To all whom it may concern:

Be it known that I, CROMWELL A. B. HALVORSON, Jr., a citizen of the United States, residing at Lynn, in the county of Essex 5 and State of Massachusetts, have invented certain new and useful Improvements in Arc-Lamps, of which the following is a specification.

My invention relates to electric arc lamps 10 and has for its object to improve the construction and operation of the same.

In the ordinary luminous arc lamp having a negative electrode of magnetite, titanium compound or similar materials 15 which give a luminous or flaming arc, the amount of light which can be obtained from a single arc is limited by the amount of energy which can be effectively consumed in the arc without over-heating the negative electrode so as to cause it to melt at 20 the end and produce a disagreeable flickering of the arc. In order to secure a satisfactory and efficient high-energy lamp of this character it is therefore necessary to make use of a plurality of arcs, and in one of its 25 aspects my invention consists in a novel construction and arrangement of lamp parts whereby a plurality of arcs may be effectively operated in unison so as to produce 30 an intense high-energy light without having recourse to individual high-energy arcs.

Since it may not always be necessary or desirable to use the maximum amount of light which may be obtained in a lamp of 35 the character described, the present invention contemplates means whereby different intensities of light may be obtained; and therefore, in another aspect, the present invention may be considered as relating to an 40 arc lamp so arranged that the light emanating therefrom may be varied in intensity.

While, specifically, my invention comprises a lamp having a plurality of pairs of electrodes and a plurality of arcs, the 45 method of feeding and controlling each set of electrodes is applicable to lamps having but a single pair of electrodes and a single arc; and, in a further aspect, my invention may therefore be considered as comprising 50 a novel arrangement for regulating and controlling a pair of electrodes in such a manner that the arc between them remains focused at a given point.

I prefer to obtain the increased intensity 55 of light by connecting a plurality of sets of

electrodes in parallel across the source and providing separate regulating and controlling means for each set of electrodes; and, where the positive electrodes are non-consuming, they can conveniently be mounted 60 upon a common floating support. In another aspect my invention may therefore be regarded as comprising a novel arrangement of floating electrodes mounted on a common support so that each electrode may be controlled by its own regulating magnet. 65

The various features of novelty characterizing my invention will be hereinafter particularly pointed out in the claims; but for a full understanding of my invention, 70 in its various aspects, reference may be had to the following detailed description taken in connection with the accompanying drawing, wherein:

Figure 1 is a side elevation of a lamp arranged in accordance with a preferred form 75 of my invention, the casing and globe being removed; Fig. 2 is a view taken at right angles to Fig. 1; Fig. 3 is a diagram of connections; the lamp mechanism being shown 80 conventionally, and Fig. 4 is a diagram illustrating a modification.

Referring to the drawing, 1 represents the hood of an arc lamp and 2 the platform; these are connected together by means of the usual central chimney 3 which also forms the backbone in the lamp. Beneath the platform and in alignment with the chimney is an enlarged bell-shaped fume box 4 across which extends the supporting member 5 of 90 the positive electrodes. The member 5 is arranged within vertical slots 6 in the walls of the fume box so as to be capable of limited vertical movements; normally it rests on stops such as cotter pins 7. Near the middle of this member are two electrodes 8 and 9 arranged parallel with each other and with the axis of the lamp. These electrodes may be of copper. 95

10 and 11 are the negative electrodes 100 which coöperate, respectively, with the electrodes 8 and 9. The electrode 10 is supported upon a holder 12 of any usual form carried upon the lower end of a tube 13 which projects upward through the platform 2 and is guided upon a rod 14 which projects downward from the hood and into the tube. To the upper end of the electrode-supporting tube is fastened a flexible cable 15, which passes over a pulley 16 and has 110

magnets, as shown in Fig. 4, the cores 16 and 20 being provided with pins 35 for moving these switches into their open positions and with other pins 36, for moving the switches 5 into their closed positions.

The operation of the lamp is as follows: When the current is switched on, the shunt coil 24 is energized to raise its core and the attached rod 22 and thus rock the crank bar 10 21 to move the point of the electrode 2 into contact with the point of the electrode 1. At the same time, coil 19 is energized to raise its core 20 and the corresponding end of the rocker bar 9 and to depress the opposite end 15 of the bar. The tilting movement of the bar 9 just specified will lower the electrode 1 and raise the electrode 2 until the coil 19 is short-circuited by the switch 33, when the bar will return to its original position, thus 20 effecting a rubbing contact between the points of the electrodes, provided the electrodes are sufficiently low in the fireproof cup. If the electrodes, at the moment of starting, are high in the cup, the horizontal 25 control mechanism will not move sufficiently to bring them into contact. In such case, the coil 19 will continue to operate and, in addition to the rubbing contact above described, the electrodes will be fed downward 30 by the operating engagement of the pawl 18 with successive teeth of the ratchet wheel 13. As soon as an electrical circuit through the electrodes is thus established, the coil 17 and the blow coil 27 become energized and the 35 latter operates to open the switch 28 and to interrupt the circuit through the coil 19. The action of the series coil 17, in operating the feeding mechanism, is controlled by the switch 26, which is operated by the coil 24, 40 and also by the switch 34, which is operated by the coil 17 itself. Under normal conditions, the switch 26 is closed, thus short-circuiting the coil 17, this switch only coming 45 into operation when the voltage across electromagnet 24 rises above a predetermined value. When such a condition occurs, the switch 26 is opened and the coil 17 becomes fully energized to raise the link 15 and thus 50 cause the pawl 14 to move the ratchet wheel 13, the distance of one tooth. The coil 17 is then short circuited by the closing of the switch, and the link drops to permit the pawl to engage another tooth of the ratchet wheel 13, this feeding action being repeated 55 until the electrodes 1 and 2 are in proper operating relation. The action of the coil 19 takes place only when the current is unable to complete its circuit through the electrodes, and the action immediately ceases 60 when the circuit becomes established through the blow coil 27.

Referring now to the remaining figures of the drawings, a modification is shown in which, instead of giving to the electrodes a 65 rubbing action only at the time of starting

the lamp, the electrodes 1 and 2 are provided, respectively, with a ratchet wheel 29, and pawls 29^a and 29^b and with a ratchet wheel 30 and pawls 30^a and 30^b, the rocker bar 9 serving to feed the carbon electrodes 70 independently and alternately, the carbon holders 3 and 4 being respectively provided with cords 31 and 32 that are connected to separate weights 31^a, 32^a.

When current is supplied to the lamp 75 shown in Figs. 5 to 8, the shunt coil 24 will first be energized to raise the rod 22 and turn the crank bar 21 to move the point of the electrode 2 into engagement with or into proximity to the point of the electrode 1. 80 If the electrodes are not in position to perform their functions, current will flow through the switch 28 and the coil 19, the switch 26 having been opened by the pin with which the core of the coil 24 is provided. The coil 19, being thus energized, will raise its core and the end of the bar 9 to which it is attached and thus cause the pawl 29^b to move the ratchet wheel 29 an amount corresponding to one tooth and thus 85 feed the electrode 2 downward a corresponding amount. The upward movement of the core of coil 19 will close the switch 33 and thus short circuit the coil to permit the core to descend by the action of gravity. As the 90 core descends, the pawl 30^a will actuate the ratchet wheel 30 to feed the electrode 1 downward an amount represented by one tooth and the switch 33 will be opened, the wheel 29 and 30 being respectively held 95 against backward movement by the pawls 29^a and 30^a. When the circuit is completed through the electrodes, the coil 27 will open the switch 28 and the coil 19 will be shunted 100 through the switch 26 until the operating 105 conditions demand renewed feeding of the electrodes.

The invention may evidently be carried out in many ways and the forms of lamp described are intended merely by way of illustration and may obviously be considerably varied without departing from the scope of the invention.

Having now described my invention, what I claim as new and desire to secure by Letters Patent, is:—

1. In an arc lamp, a pair of inclined converging electrodes, means for causing the electrodes to approach each other transversely, and means simultaneously actuated therewith for moving one electrode longitudinally with reference to the other electrode.

2. In an arc lamp, a pair of inclined converging electrodes, means for causing the electrodes to approach each other transversely, and simultaneously actuated means for effecting relative longitudinal movement of the electrodes.

3. In an arc lamp, a pair of inclined con-

- verging electrodes, means for causing the electrodes to approach each other transversely, and simultaneously actuated means for effecting relative longitudinal movement of the electrodes, said means comprising a ratchet and pawl mechanism for feeding the electrodes axially. 5
4. In an arc lamp, a pair of inclined converging electrodes, means for causing the electrodes to approach each other transversely, and simultaneously actuated means for effecting relative longitudinal movement of the electrodes, said means also feeding the electrodes axially independent of said 10 first means.
5. In an arc lamp, a pair of inclined converging electrodes, means for causing the electrodes to approach each other transversely, and simultaneously actuated means 15 for effecting relative longitudinal movement of the electrodes, said means comprising a rocker arm, a pawl mounted thereon, and a ratchet wheel which engages said pawl in order to feed the electrodes axially. 20
6. In an arc lamp, a pair of inclined converging electrodes, means for causing the electrodes to approach each other transversely, and means for effecting longitudinal movement of the electrodes, said means 25 comprising a rocker arm, a pawl mounted thereon, and a revolvable ratchet wheel from which the electrodes are suspended and
- which is adapted to engage said pawl in order to feed the electrodes axially. 35
7. In an arc lamp, a pair of inclined converging electrodes, means for causing the electrodes to approach each other transversely, and means for effecting longitudinal movement of the electrodes, said means comprising a revolvable ratchet wheel, a rocker arm, and a pawl thereon adapted to engage the ratchet wheel to feed the electrodes 40 axially when the rocker arm is actuated. 45
8. In an arc lamp, a pair of inclined converging electrodes, a supporting cord or chain for each electrode, a pulley for each cord or chain, a rocker arm upon the ends of which said pulleys are mounted, and means for rocking said arm to produce relative movement between the electrodes. 50
9. In an arc lamp, a pair of inclined converging electrodes, means for producing a forward axial movement of both electrodes, means for producing a relative axial movement between the two electrodes and means 55 for producing a relative angular movement between the two electrodes.

In testimony whereof, I have hereunto subscribed my name this fifth day of January 1909.
